(57) **CLAIM**

What is claimed is the ornamental design for a part of
milling machine, as shown and described.

DESCRIPTION

FIG. 1 is left front perspective view of the part of milling
machine. A perspective view rotated 180 degrees about a
lengthwise axis of the part of milling machine would be
identical.

FIG. 2 is right rear perspective view of the part of milling
machine of FIG. 1. A perspective view rotated 180 degrees
about a lengthwise axis of the part of milling machine would
be identical.

FIG. 3 is a top view of the part of milling machine of FIG.
1.

FIG. 4 is a front view of the part of milling machine of FIG.
1.

FIG. 5 is a bottom view of the part of milling machine of
FIG. 1.

FIG. 6 is a left end view of the part of milling machine of
FIG. 1.

FIG. 7 is a right end view of the part of milling machine of
FIG. 1; and,

FIG. 8 is a back view of the part of milling machine of FIG.
